INVENTOR

James Maloney

UNITED STATES PATENT OFFICE.

JAMES MALONEY, OF PROVIDENCE, RHODE ISLAND.

CARTRIDGE CAPPER AND DECAPPER.

SPECIFICATION forming part of Letters Patent No. 334,449, dated January 19, 1886.

Application filed November 18, 1885. Serial No. 183,173. (No model.)

To all whom it may concern:

Be it known that I, JAMES MALONEY, of Providence, in the State of Rhode Island, have invented a new and useful Cartridge Capper and Decapper; and I do hereby declare that the following specification, taken in connection with the drawings making a part of the same, is a full, clear, and exact description thereof.

10 Figure 1 is a vertical section of my improved device with cartridge-case attached. Fig. 2 is an elevation of my device with cartridge-case attached, the swing of the stud being indicated by dotted lines. Fig. 3 is an elevation 15 of my device with the cartridge-case removed.

The object of my invention is to provide an instrument for removing the exploded caps from central-fire cartridge-cases and securing 20 new caps thereto, which shall be superior in construction and facility of operation to those now in use; and it consists in the arrangement 25 of the devices for such purposes, as hereinafter described.

25 In the drawings the device is represented, for facility of illustration, in an inverted position from that in which it is practically used.

A is the frame, to one end of which is hinged a stud, B.

30 C is the cartridge-case.

D is a perpendicular shaft, extending partly through the stud B, and having upon one end a punch, E, and at the other a flat lever or disk, F. The interior of the stud B is hollow, 35 such cavity being partially closed at one end to form a bearing for the shaft D. The shaft D is provided with a transverse stud, G, within the stud B, which operates upon an inclined surface and against the resistance of a spring, 40 H, to throw forward the shaft D and operate the punch E.

I is a perpendicular shaft in the frame A, which is provided with a flat lever or disk, J, and a transverse stud, K, which also operates 45 upon an inclined surface and against the resistance of a spring, L, to throw forward the shaft I.

The operation of my invention is as follows: The stud B is swung outward upon its hinge 50 until it reaches the position indicated by the dotted lines, Fig. 2, when the cartridge case

C is placed upon it and the stud B moved into position, as shown in Figs. 1 and 2, the extended rim of the case passing under a ledge, M, in the frame A, which prevents any perpendicular movement of the case during the 55 subsequent operations. The entire device, with the case adjusted and held as described, is clasped by the left hand of the operator. The disk F is turned with the other hand, and with sufficient force to move the stud G upward upon its inclined surface and overcome 60 the resistance of the spring H and impart a perpendicular movement to the shaft D. This perpendicular movement of the shaft D brings 65 the punch E in contact with and forces out the cap N, Fig. 2, which falls out of the way. Upon releasing the lever F, the punch E is withdrawn by the action of the spring H, surrounding the shaft D, the spring being suitably 70 confined to obtain such action by a stop upon such shaft. A new cap is now placed in position and the lever J turned in the proper direction, which carries inward the shaft I (in the same manner as the shaft D, before described, is operated) until the end thereof 75 comes in contact with the cap N and forces it into place, when the stud B is again swung upon its hinge, the case removed and another put on, and the whole operation repeated. 8c

What I claim as my invention, and desire to secure by Letters Patent, is—

1. In a hand capper and decapper for cartridge-shells, the combination, with the frame A, having a spring capping implement in one 85 end, of the stud, as B, hinged to other end of frame A, and having the spring decapping implement in it, substantially as set forth.

2. In a capper and decapper, the combination, with frame A and hinged stud B, each 90 having inclined surfaces, substantially as described, of the spring-shaft I, having projection for riding over inclined surface or frame A, and spring-shaft D, having projection for riding over inclined surface on part B, and 95 means, substantially as described, for operating the shafts.

JAMES MALONEY.
